UNITED STATES PATENT OFFICE

LOUIS G. MILLER, OF BETHLEHEM, PENNSYLVANIA, ASSIGNOR TO BETHLEHEM
STEEL COMPANY

BRAKE-BEAM FOURTH-POINT SUPPORT AND SAFETY DEVICE FOR CLASP BRAKES

Application filed May 4, 1927. Serial No. 188,647.

My invention relates to brake mechanism for car trucks and more particularly to trucks of the four wheel type, on which clasp-brakes are used, wherein the brakes are forced upon 5 opposite sides of the tread of each of its four wheels simultaneously.

One of the objects of my invention relates more especially to trussed break-beams and a four point suspension for supporting the 10 brake-beams at their intermediate points. The features constituting the four point suspension consists, in addition to the customary link or hangers, not shown, which are connected to brake-beam heads and attached to the 15 truck side frames in the usual well known manner, of two pairs of track-bars, each pair having their ends secured to the spring plank and extending outwardly therefrom under the axles and supported at the outer ends by 20 brackets secured to the ends of the truck frame. Each pair of track-bars have ways thereon to engage two brake-beams at opposite sides of the struts or brake lever posts and these ways are formed at suitable angles to 25 receive, support and guide the truss-rods of the beams at their end portions, during the movement of the brake-beams so as to assure a correct positioning of the brake-beams and maintain a concentric relation of the working faces of the brake-shoes to the tread of 30 the car wheels, both in the service application of said shoes to the wheels and their release therefrom under all conditions as to the wear of either the shoes or wheels or both thereof.

Another object of my invention consists in 35 securing the track-bars to the spring-plank in such a manner that they will be held securely in their operative position, but can be easily removed or replaced on the truck to facilitate the more easy removal and replacement of the brack-beams without the removal of rivets, bolts, cotter-pins or the like, whereby the building of trucks as well as making repairs to the same is greatly facilitated.

A further object of my invention resides in 40 securing chairs to the track-bars on the ways on each side of both of the axles for receiving and supporting the truss-rods of the brake-beams at their intermediate points, said chairs

being free to slide on the ways of the track-bar members but permanently secured thereto.

Having thus given a general description of my invention, I will now in order to make the 55 same more clear, refer to the annexed two sheets of drawings, which form part of this specification, and in which like characters of reference indicate like parts:

Fig. 1 is a top plan view illustrating my 60 improved four point suspension in full lines as applied to a clasp-brake rigging, and showing enough of the adjacent portions of the truck to illustrate the application of my invention;

Fig. 2 is a sectional elevation taken on the line II—II of Fig. 1 showing parts of the 65 track-bars broken away to more clearly illustrate the construction;

Fig. 3 is a sectional detail taken on the 70 line III—III of Fig. 2 showing more clearly the manner of securing the end of one of the track-bars to the spring-plank;

Fig. 4 is a transverse section of one of 75 the chairs illustrating the manner of securing the chairs on the track-bars; and,

Fig. 5 is a detail of one of the brackets 80 which are secured to the ends of the truck frames for supporting the outer ends of the track-bars.

Referring now to the characters of reference, the numeral 10 indicates the spring-plank, 11 the brake-beams, each comprising a truss-rod or tension member 12, compression member 13, and strut 14, each adapted to take 85 the usual brake-lever, not shown. These brake-beams are disposed as is the usual case when clasp-brakes are used on each side of the tread of the wheel normally slightly below the central horizontal line of the axles as will be clearly understood by referring to Figs. 1 and 2 of the drawings.

Each pair of brake-beams is supported on 90 each side of the struts by means of track-bars 15, formed with inclined slide-ways 16, slotted as at 17 to receive the lugs 18 of chairs 19, having sockets formed therein as at 20 for engaging the truss-rods 12 of the brake-beams. The chairs are slidably mounted on the slide-ways, but are each permanently se- 100

cured to the track-bars 15 by means of a rivet 21 which passes through the lugs and is secured thereto. The inner ends 22 of the track-bars 15 are removably supported by keepers 23 which are secured to the spring-plank 10, by means of rivets 24, while the opposite ends of the track-bars are supported by means of brackets 25, attached to the end frames 26 of the truck by means of rivets 27. In order to hold the track-bars in their normal position and prevent longitudinal movement, each track-bar is offset near its inner and outer ends as at 28 and 29 respectively. The track-bars 15 are also held in position by the weight of the brake-beams which prevents normally any vertical movement of the track-bars at their outer ends which are supported by the brackets 25.

In operation the brake-beam tension members rest in the sockets on the sliding chairs which can move freely longitudinally on the slide-ways. These chairs sliding on the inclined slide-ways maintain the brake-shoes in a concentric position with relation to the tread of the wheels at all times. In case of failure of brake-beams or hangers the track-bars prevent the beams from falling on the rails.

If it is desired to remove the brake-beams, one or both of the brake-beams can be removed after hangers and other attachments are disconnected by raising the ends of track-bars which rest on the brackets 25 above the upwardly extending projection 30 of the brackets and moving them over sidewise until the track-bars are free of the brackets. They can then be lowered to disengage the chairs from the truss-rods of the brake-beams and are then moved longitudinally until they are free from the keepers, after which they can be lowered permitting the beams to be removed.

It will be noticed by referring to the drawings that the track-bars are mounted in such a way as to allow them to be attached or detached from the truck frame without removing bolts, rivets, pins or cotter-pins or the like.

Although I have shown and described my invention in considerable detail, I do not wish to be limited to the exact and specific details shown and described, but may use such substitutions, modifications or equivalents thereof as are embraced within the scope of my invention or as pointed out in the claims.

Having thus described my invention what I claim and desire to secure by Letters Patent is:

1. In a fourth point support for clasp-brakes, comprising a centrally mounted spring-plank and end frames, track-bars having their ends supported by the spring-plank and end frames oppositely downwardly inclined slotted slide-ways formed on

the track-bars, a chair slidably mounted on each slide-way adapted to support the brake-beams at intermediate points, a lug formed integral with the chair extending through the slots in the track-bar, and a rivet extending through the lug formed on the chair for securing the chair permanently to the track-bars.

2. In a fourth point support for clasp-brake-beams, comprising a truck frame having a centrally disposed spring-plank and end frames, a pair of track-bars mounted on each side of the spring-plank and removably secured to the spring-plank and end frames, each of said track-bars having an arc-shaped central portion adapted to extend under the car axles, slotted slide-way portions extending downwardly from each central arc-shaped portion of the track-bars, chairs movably mounted on the slide-way for supporting the brake-beams, lugs formed integral with the chairs extending through the slots in the slide-ways, rivets extending through the lugs for permanently securing the movable chairs to the track-bars, and abutments formed on the track-bars to prevent longitudinal movement of the track-bars.

3. In a fourth point support for brake-beams, comprising a track-bar secured to the truck frame having a central arc-shaped portion with downwardly extending slotted slide-ways formed on each side of the said central portion, chairs movably mounted on the slotted slide-ways, and abutments formed on the track-bars to prevent longitudinal movements of the track-bars.

4. In a fourth point support for brake-beams secured to the truck frame, comprising track-bars each having a central arc-shaped portion adapted to extend under the axle of the car truck, downwardly extending slotted slide-ways formed on each side of the arc-shaped central portion, movable chairs permanently secured to the slotted slide-way portions of the track-bars, and abutments formed near each end of the track-bars to normally prevent longitudinal movement of the track-bars.

5. In a fourth point support for brake-beams, comprising a plurality of track-bars arranged in pairs on each side of a centrally located spring-plank and supported by the spring-plank and the end frames of the truck, said track-bars each having a central arc-shaped portion adapted to extend under the axles of the car truck, downwardly extending slotted slide-ways formed on each side of the arc-shaped central portion, movable chairs permanently secured to the slotted slide-way portions of the track-bars, and abutments formed near each end of the track-bars to normally prevent longitudinal movement of the track-bars.

6. In a fourth point support for brake-beams, comprising a truck-frame having end

- frames and a centrally mounted spring-plank, track-bars each having a central arc-shaped portion with downwardly inclined slide-ways and straight horizontally disposed end portions, said straight end portions of the track-bars being removably supported on the spring-plank and end frames, offsets formed in the track-bars, trussed brake-beams having brake-shoes for engaging the opposite sides of the tread of the wheels, said trussed brake-beams adapted to engage the slide-ways and retain the track-bars in position. 5
7. In a fourth point support for brake-beams, comprising a truck-frame having end frames and a centrally mounted spring-plank, track-bars each having a central portion with downwardly inclined slide-ways, said track-bars having their inner ends slidably secured to the spring-plank and their outer ends seated in brackets secured to the end frames, and trussed brake-beams having brake-shoes for engaging the opposite sides of the tread of the wheels, and adapted to 10 be supported at an intermediate point on the slide-ways and retain the track-bars in position. 20
8. In a fourth point support for brake-beams, comprising a truck-frame having end frames and a centrally mounted spring-plank, track-bars each having a central portion with downwardly inclined slide-ways, movable chairs permanently attached to the slide-ways, said track-bars having their inner ends slidably secured to the spring-plank and their outer ends seated in brackets attached to the end frames, trussed brake-beams having brake-shoes for engaging the opposite sides of the tread of the wheels and adapted 25 to be supported at an intermediate point by the chairs mounted on the slide-ways, and means unattached thereto for holding the track-bars in position. 30
9. In a fourth point support for brake-beams, comprising a truck-frame having end frames and a centrally mounted spring-plank, track-bars each having a plurality of slide-ways formed thereon extending between the spring-plank and end frames, means on 35 the spring-plank and end frames for holding the opposite ends of the track-bars unattached thereto, and brake-beams supported at an intermediate point on the slide-ways of the track-bars for retaining the track-bars 40 in position. 50
10. In a fourth point support for brake-beams, comprising a truck frame having a spring-plank and end frames, track-bars each having an arc-shaped central portion 45 with downwardly inclined slotted slide-ways and straight horizontally disposed ends removably supported on the spring-plank and end frames, an offset formed in the track-bars between each of the inclined slide-ways and 55 the straight end portions, chairs movably
- mounted on the slide-ways and permanently secured thereto, and trussed brake-beams mounted upon the track-bars and supported at their intermediate points by the chairs. 60
11. In a fourth point support for brake-beams, comprising a truck frame provided with a spring-plank and end frames, track-bars, means unattached to the track-bars for removably securing the opposite ends of the track-bars to the spring-plank and end frames, each of said track-bars having an arc-shaped central portion and downwardly inclined slide-way intermediate portions, a chair permanently secured to each of the slide-way portions, and brake-beams supported 65 at their intermediate points by the chairs. 70
12. In a fourth point support for brake-beams, comprising a truck frame having end frames and a centrally disposed spring-plank, a pair of unattached track-bars mounted on 75 each side of the spring-plank and removably secured to the spring-plank and end frames, each of said track-bars having a central arc-shaped portion adapted to extend under the car axle, slide-way portions extending downwardly from the central arc-shaped portion of the track-bars, a chair permanently secured to and slidably mounted on each of the slide-ways, and brake-beams supported at intermediate points by the chairs. 80
13. In a fourth point support for brake-beams, comprising a truck-frame having end frames and a centrally disposed spring-plank, a pair of unattached track-bars slidably mounted on each side of the spring-plank and 85 removably secured to the spring-plank and end frames, each of said track-bars having a central arc-shaped portion adapted to extend under the car axle and having slotted slide-way portions extending downwardly from each central portion of the track-bars, chairs movably mounted on the slide-ways, lugs formed integral with the chairs adapted to extend through the slots formed in the slide-way portions, means attached to the 90 lugs for permanently securing the movable chairs to the track-bars, and brake-beams supported at intermediate points by the chairs. 95
14. In a fourth point support for brake-beams, comprising a truck-frame having end frames and a centrally disposed spring-plank, a pair of unattached track-bars secured to the truck-frame each having a central arc-shaped portion with downwardly extending slotted slide-ways formed on each side of the said 100 central portion, chairs movably mounted on the slotted slide-ways, offsets formed on the track-bars to prevent longitudinal movement of the track-bars, and brake-beams supported at intermediate points by the chairs. 105
- In testimony whereof I hereunto affix my signature. 110
- LOUIS G. MILLER. 130
